(57) **CLAIM**

The ornamental design for a nut seal assembly for a coaxial connector, as shown and described.

DESCRIPTION

FIG. 1 is a perspective view of a new and ornamental nut seal assembly for a coaxial connector;

FIG. 2 is a top plan view of the nut seal assembly for a coaxial connector, bottom plan view being identical thereto;
FIG. 3 is a side view of the nut seal assembly for a coaxial connector, the other side being a mirror image thereof;
FIG. 4 is a nut end view of the nut seal assembly for a coaxial connector;

FIG. 5 is a cable end view of the nut seal assembly for a coaxial connector;

FIG. 6 is a perspective view of the nut seal assembly for a coaxial connector;

FIG. 7 is a top plan view of the nut seal assembly for a coaxial connector, the bottom plan view being identical thereto;

FIG. 8 is a side view of the nut seal assembly for a coaxial connector, the other side being a mirror image thereof;

FIG. 9 is a nut end view of the nut seal assembly for a coaxial connector; and,

FIG. 10 is a cable end view of the nut seal assembly.

The broken line showing of nut seal assembly for a coaxial connector is for illustrative purposes only and forms no part of the claimed design.
